UNITED STATES PATENT OFFICE.

FERDINAND HUBERT, OF NEW YORK, N. Y.

DESIGN FOR A BREAD-BAKING PAN.

SPECIFICATION forming part of Design No. 32,756, dated May 29, 1900.

Application filed May 5, 1900. Serial No. 15,648. Term of patent 14 years.

To all whom it may concern:

Be it known that I, FERDINAND HUBERT, a citizen of the United States, residing at New York, (Brooklyn,) in the county of Kings and State of New York, have invented and produced a new and original Design for a Bread-Baking Pan; and I do hereby declare the following to be a full, clear, and exact description of the same, reference being had to the accompanying drawings, forming a part thereof.

In said drawings, Figure 1 is a perspective view of the pan turned upside down. Fig. 2 is a longitudinal vertical section of the pan on a line passing through the deepest portion of its corrugated half.

Referring to the accompanying drawings and to the letters thereon, it will be observed that in design my form of bread-baking pan comprises two sections A and C of equal width extended the length of the pan and separated by an inwardly-projecting ridge D, so that an end view of the pan has the appearance of a capital letter "B."

When the pan is standing in the position

shown in Fig. 1, the top of the section A of the pan has a smooth surface substantially half-cylindrical; but the top of the section C has a series of arched crimps or corrugations E of uniform width extended across the length 30 of said section C part way, indenting it at right angles to its longitudinal center.

The leading feature of the design is found in the two halves or sections of the pan formed so that the bottom of one of said sections is an inverted arch smooth-surfaced, and the bottom of the other section presents crimps or corrugations across its surface. 35

Having thus described my invention, what I claim, and desire to secure by Letters Patent, is—

The design for a bread-baking pan as herein shown and described.

In testimony whereof I affix my signature in presence of two witnesses.

FERDINAND HUBERT.
